UNITED STATES PATENT OFFICE

LAWRENCE L. COOK, OF INDIANAPOLIS, INDIANA

AMUSEMENT DEVICE

Application filed March 19, 1929. Serial No. 348,308.

This invention relates to amusement devices and has relation more particularly to a device of this kind adapted to simulate pitching of horseshoes, and it is primarily an object of the invention to provide a device of this kind which can be readily employed as an indoor game.

Another object of the invention is to provide a device of this kind comprising a figure in simulation of a person and wherein said figure comprises an arm serving as a projector, said arm having means for initially gripping a horseshoe or the like and which means is automatically rendered inoperative to release the horseshoe upon swinging movement of said arm for a predetermined distance.

An additional object of the invention is to provide a device of this kind including a figure in simulation of a person, said figure being articulated to permit the same to have such movements to simulate the action of a person in throwing a horseshoe or the like.

A further object of the invention is to provide a device of this kind comprising a projector for throwing a horseshoe or the like through the air toward a target, said projector being of a character whereby its manipulation involves considerable skill on the part of the player.

The invention consists in the details of construction and in the combination and arrangement of the several parts of my improved amusement device whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan illustrating

an amusement device constructed in accordance with an embodiment of my invention;

Figure 2 is an enlarged view in side elevation of the structure as illustrated in Figure 1 with the jacket or casing for the body of the figure being diagrammatically indicated by broken lines and with the projector in position for delivering a horseshoe;

Figure 3 is a fragmentary elevational view of the figure as herein comprised and the parts directly associated therewith, the parts being in a position after the horseshoe has been delivered;

Figure 4 is a view partly in rear elevation and partly in section of the structure as illustrated in Figure 2, the section being taken on the line 4—4 of Figure 2 through the base of the device;

Figure 5 is an enlarged sectional view taken substantially on the line 5—5 of Figure 4 with a second position of certain of the parts being indicated by broken lines;

Figure 6 is a fragmentary view in front elevation of the upper portion of the structure as illustrated in Figure 5.

Figure 7 is a fragmentary view in perspective illustrating the upper portion of the post and an associated portion of the swinging member.

As disclosed in the accompanying drawings, my improved amusement device embodies only a single projector and target as this is believed to be sufficient for the purposes of disclosure although it is to be understood that a projecting mechanism may be at either end of the base B or a number of such mechanisms may be provided as desired.

The base B, as herein disclosed, is oblong in form and of desired dimensions and has its opposite end portions provided with the supporting members 1. One end portion of the base B has resting thereon a cushion 2 through which is directed an upstanding stake or target 3 carried by the base B. The

supporting members 1 at the end portion of the base B remote from the cushion 2 support a rock shaft 4 disposed transversely below the base B proper and provided at its 5 opposite extremities and outwardly of the base B with the operating levers 5. As is particularly illustrated in Figures 1, 2 and 3 these members 5 are angularly disposed one with respect to the other and substantially in perpendicular relation.

10 The base B to one side thereof and forwardly of the shaft 4 has secured thereto by riveting, as at 6, or otherwise as may be preferred, an upstanding flat post 7 of desired length and width. The upper end portion 15 of the post 7 is continued by an extension 8 substantially at right angles thereto and disposed toward the adjacent end of the base B, said extension 8 terminating in a transversely disposed and relatively short arm 9 which in turn is continued by an inwardly disposed arm 10 substantially in parallelism with the extension 8.

15 The extension 8 and arm 10 provide mountings for a pintle 11 bridging the space therebetween and with which are hingedly connected the lower extensions 12 carried by the side flanges 14 of an upstanding channel member 15 whereby the member 15 is 20 capable of swinging movement in a direction lengthwise of the base B. The member 15, however, is prevented against upward swinging movement beyond the vertical by contact of the portions of the extensions 12 25 above the pintle 11 with the arm 9 hereinbefore referred to and as particularly illustrated in Figure 5 of the drawings.

20 The post 7 below but in relatively close proximity to the extension 8 is provided with a laterally directed arm 16 underlying the pintle 11. Anchored, as at 17, to this arm 16 is the lower end portion of a leaf spring 18. This spring 18 extends upwardly between the flanges 14 and its upper free portion has constant contact with the base of 25 said member 15. This spring 18 serves to constantly urge the member 15 upwardly and at the limit of its swinging movement in such direction.

25 The flanges 14 of the member 15 at their upper ends are also provided with the extensions 19 through which is directed a rock shaft 20. This shaft 20 between the flanges 14 has fixed thereto a rock plate 21 of triangular formation, the base of which being of sufficient width to have contact with the base portion of the member 15 whereby the rock plate 21 is prevented from having downward 30 swinging movement below substantially the horizontal.

35 The outer or apex portion of the plate 21 is straddled from below by a fork 22 provided at the upper end portion of an elongated lever 23, said fork 22 being pivotally

connected by the pin 24 to the apex portion of said plate 21.

40 The lever 23 is of a length to extend through a suitably disposed slot 25 provided in the base B to one side of and immediately adjacent to the post 7 with the lower end portion of said lever 23 operatively connected, as at 26, with the free end portion of an inwardly disposed rock arm 27 movable with the shaft 4 so that upon rocking movement of the shaft 4 in one direction the member 15 will be swung downwardly and forwardly as indicated in Figure 2 of the drawings after the plate 21 has been swung down sufficiently to bring the base of said plate 21 into contact with the base portion of the member 15. It is to be stated at this time, however, that the plate 21 normally has its base in contact with the base of the member 15 due to the weight of said plate plus the weight of the lever 23 imposed thereon.

45 The rock shaft 20 extends a desired distance to one side of the member 15 and to the extremity of said extended portion is fixed a downwardly and forwardly curved elongated member or arm 28, and said member or arm 28 a desired distance inwardly of its lower free end but in relatively close proximity thereto is provided with a pair of upwardly disposed and transversely spaced lugs 29 with which is pivotally connected the rear portion of a clamping or holding member 30. The pivoted end portion of this member 30 is continued by an upwardly curved arm 31 positioned in advance of the arm 28 and interposed between these arms 28 and 31 is a spring member 32 which serves to constantly urge the plate 30 toward the outer free end portion of the arm 28 and under sufficient tension to effectively hold or clamp the article 33 therebetween. As herein disclosed, the article 33 is in simulation of a horseshoe.

50 One of the flanges 14 of the member 15 adjacent to its upper end carries a bracket 34 terminating in an outwardly disposed arm 35 intersecting the path of travel of the upper portion of the arm 31. Threaded from without through this arm 35 is an adjustable stop 36 held in desired position by the binding nuts 37 engaged thereon for contact with the opposite faces of the plate 35. As the arms 28 and 31 are moved or swung upwardly the contact of the upper free portion of the arm 31 with the stop 36 will swing the plate 30 into open or released position and at substantially the same time the member 36 will effect an abrupt stop to the forward swinging movement of the arm 28, resulting in the article or projectile 33 being thrown in a direction toward the target or stake 3, and with practice and skill a player will be able to so regulate the speed and length of travel of the arm 28 to cause the article or projectile to ring the target or stake 3 or fall upon the

cushion 2 or at a point in relatively close proximity thereto.

The opposite end portions of the shaft 20 provide a mounting for a jacket or casing

5 adapted to substantially house or inclose the member 15 and the parts immediately associated therewith, said jacket or casing 38 being indicated by broken lines in the accompanying drawings and shown in simulation of the body portion and head of a person.

10 This jacket or casing 38 in itself forms no particular part of my invention other than to give a finished appearance to the upper portion of the mechanism and to increase the simulation of an individual.

15 It is to be mentioned, however, that the lower portion of this jacket or casing 38 is open so that no hindrance or obstruction will be offered to desired swinging movement 20 of the member 15 and the parts moving therewith and it is to be further observed in Figure 4 that the arm 28 and its concomitant parts are positioned outwardly of the applied casing or jacket.

25 The inner face of the post 7 is substantially concealed by an elongated plate 39 in simulation of a leg and shown by broken lines in the accompanying drawings, said plate being preferably held in applied position by an end 30 portion of the pintle 11 hereinbefore referred to.

The opposite end portion of the pintle 11 extends a desired distance beyond the member 15 and is disposed through a slot 40 produced

35 in the upper portion of a second elongated plate 41 in simulation of a leg with the upper leg and fore leg thereof in angular relation, such as is generally assumed by a person in swinging such leg during the throwing operation of a horseshoe or kindred projectile.

40 The lower portion of this plate or leg 41 is pivotally connected, as at 42, with the free extremity of an upstanding arm 43 which extends through the opening 25 hereinbefore referred to and which has its lower portion pivotally supported, as at 44, by an adjacent supporting member 1. The pivoted portion of the arm 43 is provided with a plate 45 disposed toward the outer end portion of the arm 27 and the free portion of said plate 45 is provided with an enlarged opening 46, the pivot 26 connecting the lever 23 and arm 27 being extended to project through said opening 46.

45 As the lever 27 is swung in opposite directions contact of the pivot member 26 with the opposite end portions of the opening 46 will serve to effect a forward and rearward swinging movement of the plate or leg 41 whereby 50 the desired stepping action of a person is simulated in a realistic manner, thus materially increasing the amusement afforded by the game device.

55 The end portion of the base B upon which 60 the cushion 2 is rested may have extending

upwardly therefrom a screen of any desired character to catch the article or projectile 33 in the event it should be thrown with too much force.

From the foregoing description it is 70 thought to be obvious that an amusement device constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. An amusement device of the class described comprising a base, an upstanding post mounted thereon, a member pivotally engaged with said post and extending upwardly therefrom, said post having a stop with which said member contacts to limit the upward swinging movement of the member, means for normally maintaining said member at said limit of movement, a projector arm carried by said member, and means for imparting requisite movement to the projector arm, said means also operating to impart downward swinging movement to the member.

2. An amusement device of the class described comprising a base, an upstanding post mounted thereon, a member pivotally engaged with said post and extending upwardly therefrom, said post having a stop with which said member contacts to limit the upward swinging movement of the member, means for normally maintaining said member at said limit of movement, a projector arm carried by said member, means for imparting requisite movement to the projector arm, said means also operating to impart downward swinging movement to the member.

3. An apparatus of the class described comprising a pivoted member, a mounting for said member, a rock shaft carried by the member, an elongated arm fixed to the rock shaft, means for rocking said shaft cooperatively with said member, a clamping plate overlying the outer extremity of the arm, means for pivotally connecting said plate to the arm, the pivoted end portion of the plate being provided with an extension, means for constantly urging the plate toward the adjacent extremity of the arm, and an adjustable stop carried by the member with which

the extension of the plate contacts upon movement of the arm in one direction to move the clamping plate into release position and to limit the swinging movement of the arm in such direction.

5. 4. A device of the class described comprising a member, a supporting means therefor, a rock shaft carried by said member, an arm carried by the shaft, clamping means carried by the arm, said clamping means and member having coating means for releasing the clamping means upon swinging movement of the arm a predetermined distance in one direction, a rocking plate carried by the shaft, said plate coating with the member for limiting the swinging movement of the arm in the opposite direction, a lever operatively engaged with said plate, and means for operating the lever to impart rocking movement to the shaft.
- 10 15 20 25 30

5. A device of the class described comprising a post having a part extending to one side thereof, a leg member extending along the post, the upper portion of the leg member having a slot through which said projecting part is directed, a rock shaft, and an operative connection between the rock shaft and the lower portion of the leg member for imparting swinging movement to the leg member upon operation of the shaft.

- 35 40 45
6. A device of the class described comprising a post having a part extending to one side thereof, a leg member extending along the post, the upper portion of the leg member having a slot through which said projecting part is directed, a rock shaft, a swinging lever supported below the leg member, one end portion of the lever being operatively engaged with the leg member, an outstanding plate carried by the opposite end portion of the lever provided with a relatively large opening, a rock arm supported adjacent to said plate and having a part extending through the opening of the plate, said part being of a diameter materially less than that of the opening, and means for operating said rock arm.

7. An amusement device of the class described comprising a base, supporting means upstanding from said base, a pivoted member mounted on said supporting means and extending upwardly therefrom, an outstanding shaft carried by said pivoted member adjacent the upper end portion thereof, projecting means mounted on said shaft, releasing stop means mounted on said pivoted member and adapted to limit the movement of said projecting means, a depending member pivotally carried by said supporting means, and operating means adapted to rock said pivoted member and cooperatively swing said projecting means and said depending member.

- 60 65 66
8. An amusement device of the class described comprising a base, supporting means

upstanding from said base, a pivoted member on said supporting means, projecting means outstanding from said pivoted member, stop means on said supporting means for limiting the movement of said pivoted member, yieldable means mounted on said supporting means and engaging said pivoted member whereby to swing said pivoted member upwardly, and operating means for said pivoted member and said projecting means.

70

In testimony whereof I hereunto affix my signature.

LAWRENCE L. COOK.
